UNITED STATES PATENT OFFICE.

ARTHUR L. MACBETH, OF BALTIMORE, MARYLAND, ASSIGNOR TO DAYLIGHT MOTION PICTURE CO., OF WASHINGTON, DISTRICT OF COLUMBIA, A CORPORATION OF WEST VIRGINIA.

PROJECTION SCREEN.

No Drawing. Application filed November 16, 1925. Serial No. 69,500.

This invention relates to projection screens and is designed primarily for use in the daylight exhibition of projected pictures.

5 As disclosed in my Patent 1,419,281, issued June 13, 1922, it is desirable, in order to properly display projected pictures in daylight, to locate the projector back of a dark compartment or projecting chamber 10 and to focus the rays from the projector upon the back of a screen forming a portion of the front wall of said chamber. It has been found that, in order to obtain satisfactory results, the screen must be both 15 translucent and opalescent and must have the property of preventing the passage therethrough of glaring rays that would mar the vision and be injurious to the eyes of persons seated in front of the screen.

20 It is an object of the present invention to provide a screen which is inexpensive to produce and which overcomes the disadvantages mentioned by meeting the stated requirements.

25 With the foregoing and other objects in view, which will appear as the description proceeds, the invention consists of certain novel details and combinations which will be hereinafter more fully described and pointed out in the claims, it being understood that various changes may be made 30 therein within the scope of the claims, without departing from the spirit of the invention.

35 In making the screen there is provided a base of a suitable fabric such as silk, linen or cotton. Under some conditions it has been found desirable to first saturate this fabric with a liquid which will act as a 40 filler and a size. In practice the best preparation for this purpose thus far discovered has been the fresh blood of bullocks diluted with water. After this initial treatment the fabric is allowed to dry and will become of an amber colour.

45 As before stated this first treatment is not always necessary but is dependent upon the kind of fabric used. Whether or not the fabric is given the initial treatment described, it is next saturated by dipping or the like, with a mixture consisting of the

following ingredients substantially in the proportions stated, to wit:

	Parts by bulk:
Canadian balsam	2 55
Oil of sassafras	2
Litharge	1
Pure linseed oil	5

The foregoing ingredients are thoroughly 60 mixed and the fabric is submerged therein so as to become saturated. Thereafter surplus material is wiped from the surface of the fabric and said surface is rubbed so as to be left smooth. The screen thus produced is allowed to dry and the resultant 65 article will be translucent and opalescent and will act as a screen to prevent the passage therethrough of the glare or bright rays which would otherwise prevent satisfactory use of the screen.

70 In the mixture constituting the treating material the Canadian balsam acts as a binder for holding the preparation to the fabric and, in a sense, has the same properties as the diluted bullocks' blood. The oil of sassafras increases the penetrating 75 quality of the mixture and the litharge gives body thereto. The linseed oil forms the main ingredient and serves to give the 80 screen a smooth, weatherproof surface having the desirable sheen.

When images are projected against the back of a screen made as herein described, they will be displayed in a soft restful light 85 through the screen and will be plainly visible in daylight when the conditions are met as called for in my patent hereinbefore mentioned.

It might be stated that an added advantage 90 in using oil of sassafras in the mixture is that this oil has been found to prevent discoloration of the screen under the action of light rays.

95 What is claimed is:

1. A projection screen including a fabric base, and heat and moisture resisting means for rendering the base translucent, opalescent and weatherproof, said means including a solution of Canadian balsam, and linseed oil. 100
2. A projection screen including a fabric base, and heat and moisture resisting means

for rendering the base translucent, opalescent and waterproof, said means including Canadian balsam, linseed oil, and oil of sassafras.

5. A projection screen including a fabric base, and heat and moisture resisting means for rendering the base translucent, opalescent and weatherproof, said means including Canadian balsam, linseed oil, oil of sassafras 10 and a filler.

6. A projection screen including a fabric base, and means for rendering the base

translucent, opalescent and weatherproof, said means including a mixture of Canadian balsam, oil of sassafras, litharge and linseed oil. 15

7. A projection screen including a fabric base impregnated with a mixture of the following ingredients substantially in the proportions stated, to wit, Canadian balsam, 20 two parts by bulk, oil of sassafras, two parts by bulk, litharge, one part by bulk, and linseed oil, five parts by bulk.

ARTHUR L. MACBETH.
